BY

Paul Z. Fornay
ATTORNEY.

UNITED STATES PATENT OFFICE.

CLARENCE L. STOGLIN, OF SAN ANTONIO, TEXAS.

SHINE STAND.

Application filed April 19, 1926. Serial No. 102,945.

This invention relates to shining stands particularly adapted for use in shining parlors or the like where it is desired to give the best of service to customers by making 5 the equipment as safe and as neat as possible.

One of the primary objects of the present invention is the contemplation of a shining stand which includes the feature of a foot 10 rest which may be dropped or closed to a position entirely out of the way when the customer takes or leaves the seat to have his shoes or boots shined.

Another object of the instant invention is 15 to provide a shine stand having a clear unobstructed step and platform when the foot rests thereof are in the closed position and when the auxiliary step thereof is dropped to the open position.

Still another object of my invention is 20 the provision of new and novel means for operating the foot rests thereof to the open and closed position, which operating means may be housed beneath the platform and 25 operated from in front of the same with ease.

Many minor objects of the invention will 30 appear during the course of the detailed specification referring to the accompanying drawing in which:

Figure 1 is a front elevation of a shine stand made in accordance with the present invention, with the foot rests in the lowered or inoperative position.

Fig. 2 is a side elevation of the same.

Fig. 3 is an enlarged vertical central section of the shine stand taken on line III—III of Fig. 1.

Fig. 4 is a cross section of the stand taken 40 along line IV—IV of Fig. 3.

Fig. 5 is a fragmentary section taken on line V—V of Fig. 4, and,

Fig. 6 is a detailed section through one of 45 the wheel hubs showing the flanges integral with the shaft.

Similar reference characters refer to like parts throughout the several views, and the numeral 7 designates a platform, made of any suitable material and having the top 50 thereof stepped to provide a higher and a lower portion as shown in Fig. 2. A seat in the form of a bench or chair 8 is mounted on the higher portion of the platform 7, and the central part of the raised portion 55 should be cut back at the front to provide a recess 9 as shown in Fig. 3.

The support part 10 of foot rests 12 is a part of the floor of the lower front portion of the platform 7, and is pivoted near the forward end by pins 13 or the like which 60 permit the foot rests 12 to be swung to the open or closed position. When in the closed position, foot rests 12, of which there are two, are disposed parallel to and very close to the vertical wall connecting the high and 65 low portion of platform 7. These foot rests 12 are at the free end of the support part 10, which is bifurcated and extends on each side of a projecting part 14, which is a part of the floor or platform 7.

When foot rests 12 are in the closed or inoperative position, the customer is permitted to mount the platform 7 and seat 8 through the use of an auxiliary step 15, pivoted to the front wall of platform 7 as 70 at 16, and supported at its outermost end by a leg plate 17, which is hinged to step 15 in a manner shown at 18 to permit step 15 and leg plate 17 to lie flatly together when raised to enter opening 19 formed in 75 the front wall of the platform. Stops 20 preclude the auxiliary step from falling too far back when in the closed position, and hold the same in the same plane as the front wall of the platform when not in use.

After a customer has ascended to the seat 8, the operator closes auxiliary step 15 and proceeds to draw foot rests 10 to the vertical position, shown in dotted lines of Figs. 3 and 4 where the same may be conveniently 80 engaged by the customer's feet.

Novel and simple operating means has been provided to open and close the foot rests from the operator's position in front of the platform.

One form of embodiment of the mechanism is here shown to be a pair of flexible cables 21 and 22 which, when pulled, open and close, respectively, the footrests. Each cable 21 and 22 extends through suitable 95 openings in the front wall of the platform 7 and around sheave wheels 23, mounted on a transverse shaft 24 supported in any suitable manner beneath the platform.

The inner end of cable 21 engages a 105 bracket 25 at a point in front of pivotal point 13, as clearly shown in Fig. 5. When handle 26 is pulled, cable 21 is pulled around sheave wheel 23 (Fig. 5), and a downward and outward pull is imparted to bracket 25 which opens or raises foot rest 10 to the operative position. When closed,

bracket 25 has a portion 27 which engages the under side of the platform floor to keep the footrests and the supporting part from dropping.

- 5 To bring the footrests 12 to the closed position from the open position, it is but necessary to pull out on handle 28. This draws the footrest from the position shown in dotted lines to that shown in full lines 10 of Fig. 3. Bracket 29 must be engaged by cable 22 at a point to the rear of pivotal point 13, and a pin or the like 30 projects from this bracket to engage the under side of the floor to limit the opening movement 15 of footrests 12. As shown in Fig. 6, sheave wheels 23 are loosely mounted for rotation upon a shaft 24 between guide flanges 31, and the shaft does not turn when the foot rests are being raised or lowered.
- 20 The operation and many novel features of the device have been made clear throughout the specification, and it is understood that the cables described herein may be actuated in any suitable manner.

25 What I claim and desire to secure by Letters Patent is:

1. A shoe shining stand of the kind described comprising a platform, a seat mounted thereon, the seat-supporting portion of said platform being higher than the part in front of said seat, a portion of the lower floor of said platform being hingedly mounted, foot rests on said hingedly mounted portion and means for raising and lowering said portion extending through the front wall of said platform.

2. A shoe shining stand of the kind described comprising a platform, a seat mounted thereon, foot rests including a support therefor adapted to form a portion of the platform floor in front of said seat when in the inoperative position and means for raising and lowering said foot rests operatively attached to said support and projecting through the front wall of said platform.

3. A shoe shining stand of the kind described comprising a platform, a seat mounted thereon, pivotally mounted foot rests including a support therefor adapted to form a portion of the platform floor in front of said seat when in the closed and inoperative position and manually operable means for raising and lowering said foot rests extending through the front wall of said platform.

4. A shoe shining stand of the kind described comprising a platform having a seat mounted thereon, pivotally mounted foot rests including a support therefor adapted to form a portion of the platform floor in front of said seat when in the closed position and means for raising and lowering

said foot rests from in front of said platform comprising a pair of flexible cable connections, each passing around a sheave wheel supported beneath said platform from an opening through the front wall of said platform to brackets formed integrally with said foot rests adjacent its pivotal point. 65

5. A shoe shining stand of the kind described comprising a platform having a seat mounted thereon, a pivotally mounted foot rest including a support therefor adapted to form a portion of the platform floor in front of said seat when in the closed position 70 and means for raising and lowering said foot rest from in front of said platform comprising a pair of flexible cable connections each passing around a sheave wheel supported beneath the platform after entering through an opening in the front wall thereof to brackets formed integrally with said foot rest adjacent its pivotal point, the connection of said flexible cable adapted to raise said foot rest to the operative position being attached to its bracket in front of said pivotal point when the foot rest is closed and the connection of the flexible cable adapted to lower said foot rest being attached to its bracket to the rear of said pivotal point when the foot rest is closed, whereby when the respective cables are pulled through the openings in said front wall, said foot rest is pulled to the open or closed position. 85

6. In a shining stand of the character described including a platform having a step therein to form a low and a high portion, a part of the floor of said lower portion being hingedly mounted at one end whereby it 90 may be disposed in a vertical position, foot rests secured to the other end of said movable portion, said foot rests being supported parallel and in juxtaposition to the vertical wall formed by said step when in the closed 105 position.

7. In a shining stand of the character described including a platform, a pivotally mounted foot rest adapted to form a portion of the platform floor when in the closed 110 position, a pair of brackets integral with said foot rest adjacent the pivotally mounted edge and manually operable means engaging said brackets for raising and lowering said foot rest, one of said brackets having 115 means to stop the travel of said foot rest when it reaches the open position, the other of said brackets having a stop means adapted to limit the closing movement of said foot rest and support the same in the closed 120 position.

In testimony whereof I hereunto affix my signature:

CLARENCE L. STOGLIN.
